(57) **CLAIM**

The ornamental design for a toilet for facilitating bowel movements, as shown and described.

DESCRIPTION

FIG. 1 is a front view of a first embodiment for my new design for a toilet for facilitating bowel movements;

FIG. 2 is a rear view of FIG. 1;

FIG. 3 is a left side view of FIG. 1;

FIG. 4 is a right side view of FIG. 1;

FIG. 5 is a top view of FIG. 3;

FIG. 6 is a bottom view of FIG. 3;

FIG. 7 is a front view of a second embodiment for my new design for a toilet for facilitating bowel movements;

FIG. 8 is a rear view of 7;

FIG. 9 is a left side view of FIG. 7;

FIG. 10 is a right side view of FIG. 7;

FIG. 11 is a top view of FIGS. 9; and,

FIG. 12 is a bottom view of FIG. 9.
